CLAIM

The ornamental design for a shrimp steaming tray, as shown and described.

DESCRIPTION

FIG. 1 is a bottom plan view of a shrimp steaming tray showing a first embodiment of my design;

FIG. 2 is a back-side elevational view of the first embodiment;

FIG. 3 is a left-side elevational view of the first embodiment;

FIG. 4 is a right-side elevational view of the first embodiment;

FIG. 5 is a front-side elevational view of the first embodiment;

FIG. 6 is a top plan view of the first embodiment;

FIG. 7 is a bottom plan view of a second embodiment of my design;

FIG. 8 is a back-side elevational view of the second embodiment;

FIG. 9 is a left-side elevational view of the second embodiment;

FIG. 10 is a right-side elevational view of the second embodiment;

FIG. 11 is a front-side elevational view of the second embodiment; and,

FIG. 12 is a top plan view of the second embodiment.
